COMBINED AUTOMOBILE SEAT AND RECESSED SEAT BELT BUCKLE

Donald G. Radke, Rochester, Mich., assignor to Allied
Chemical Corporation, New York, N.Y.

Filed Nov. 22, 1972, Ser. No. 308,921

Term of patent 14 years

Int. Cl. D6—01

U.S. Cl. D6—48

FIG. 1

FIG. 2

FIG. 3

FIG. 4

FIG. 1 is a perspective view of a combined automobile seat and recessed seat belt buckle showing my new design.

FIG. 2 is a side elevation view with a cut-away portion of the seat shown in FIG. 1 as seen from the left side of FIG. 1.

FIG. 3 is a detailed view of the cut-away portion of FIG. 2.

FIG. 4 is a top plan view of the buckle portion of the seat of FIG. 1.

The side of the article not shown is a mirror image of the side shown while the back is conventional.

I claim:

The ornamental design for a combined automobile seat and recessed seat belt buckle, as shown and described.
